PLATE AND RECEPTACLE LIFTER

Antoni Ozdobinski, Crum Lynne, Pa.

Application January 7, 1944, Serial No. 517,416

3 Claims. (Cl. 294—99)

This invention relates to certain new and useful improvements in plate and receptacle lifters.

The primary object of the invention is to provide a plate and receptacle lifter that may also be employed for the handling of various other articles but is primarily intended for the lifting and handling of hot plates or receptacles unprovided with handles.

A further object of the invention is to provide a lifter of the foregoing character in the form of a pair of clamping arms hingedly connected together at corresponding ends, with the free ends of the arms normally resiliently spaced and adapted for movements toward each other in the gripping of a pan, receptacle or the like for the lifting and handling thereof.

It is a further object of the invention to provide a pan and receptacle lifter wherein a pair of elongated hand-gripping arms are hingedly connected together at corresponding ends with a leaf spring associated with said gripping ends for normally spacing the unconnected ends of the arms to the limits of movement under restriction of a flexible connector between the arms intermediate the ends thereof.

With the above and other objects in view that will become apparent as the nature of the invention is better understood, the same consists in the novel form, combination and arrangement of parts hereinafter more fully described, shown in the accompanying drawing and claims.

In the accompanying drawing:

Figure 1 is an edge elevational view of a pan and receptacle lifter constructed in accordance with the present invention.

Figure 2 is a side elevational view, partly in section, illustrating the two clamping arms of the lifter and the flexible connector for limiting separating movements of the free ends of the arms.

Figure 3 is a detail sectional view taken on line 3—3 of Figure 1, showing the hinge connection and the mounting for the expanding leaf spring for the arms located at corresponding ends of the arms, and

Figure 4 is a detail sectional view taken on line 4—4 of Figure 3, showing the unitary securing means for the hinge butt and leaf spring.

The device being in the nature of a pair of pliers or tongs and comprising a pair of elongated gripping arms, may be constructed of any suitable material desired and in view of the scarcity of metals, the clamping arms of the lifter may be formed of wood, plastic or other synthetic materials and, as illustrated, the lifter comprises a pair of elongated arms 5 of bar or rod-like form,

illustrated as being rectangular in cross-section, but it is to be understood that the design of these arms may be varied if desired.

Corresponding ends 5a of the arms 5 are hingedly connected together as illustrated by means of a barrel hinge member 6 carrying hinge butt plates 7 disposed at the inner adjacent sides of the ends 5a of the arms and secured thereto by screws 8 or other fastening means, the barrel portion of the hinge being disposed outwardly of the ends of the arms as illustrated whereby the free ends 5b of the arms 5 may move into closer relationship in the act of gripping a pan or receptacle. A spring device is associated with the hinged ends 5a of the arms 5 and said spring device is in the form of a leaf bent into substantially U-shape as illustrated with the legs 9 of the leaf spring received in bifurcations or slots 10 formed in the ends 5a of the arms and opening 20 at the ends of said arms. The bight 11 of the leaf spring spans the hinge barrel 7 and in the action thereof normally tends to separate the free ends 5b of the arms. To simplify the structure, the screw devices 8 or other fastening means that 25 are employed for securing the hinge butts 11 to the arms are also employed for anchoring the legs 9 of the leaf spring in position in the slotted ends 5a of the arms, this arrangement being clearly illustrated in Figures 3 and 4.

To limit the separating movements of the free ends 5b of the arms, there is provided a flexible connector 12 passing through openings 13 in the arms 5 intermediate the ends thereof with the outer extended ends of the flexible connector 12 35 knotted or headed as at 14 to provide abutments against which the outer sides of the legs engage under influence of the leaf spring 11 and the length of this flexible connector 12 may be varied for determining the separating movements of 40 the free ends 5b of the arms.

As shown in Figures 1 and 2, the free ends 5b of the arms are equipped with heads or bands 15 to facilitate gripping of a pan, receptacle or other object to be lifted and manipulated and said 45 heads or bands may be formed of any material desired, either cushioning, heat-resistant, such as plastic or the like and may be of a nature for gripping cooperation with the beaded edge of a pan, receptacle or like article.

From the above detailed description of the invention, it is believed that the use and construction thereof will at once be apparent, it being noted that the side arms 5 may be gripped at the desired points of the lengths thereof for moving the headed ends 15 towards each other

against the tension of the leaf spring 11 in the act of gripping a pan, receptacle or the like. The flexible connector 12 limits separating movement of the arms, when the device is out of use or during the releasing movement of the lifter with respect to an article with which the same was engaged, and while there is herein shown and described the preferred embodiment of the invention, it is nevertheless to be understood that minor changes may be made therein without departing from the spirit and scope of the invention as claimed.

I claim:

1. In a lifting device of the character described, a pair of elongated arms, a hinge having a pair of lateral butts with the butts respectively secured to the inner sides of a pair of corresponding ends of the arms, the hinged connected ends of the arms being bifurcated, a leaf spring of substantially U-shape with the side legs thereof respectively located between the furcations of an arm and retained therein by the hinge butt securing means, the arms having aligned openings therein intermediate the ends, a flexible cord extending through the opening in each arm and headed at its extended ends to provide arm engaging abutments for limiting separating movements of the free ends of the arms and a work-engaging head at the free end of each arm.

2. In a lifting device of the character described, a pair of elongated arms, a hinge connection between a pair of adjacent ends of the arms, a spring device associated with the hinged ends for tensioning the free ends of the arms in directions of separating movements, means associated with the arms intermediate the ends thereof for limiting separating movements of the free ends of the arms, and unitary means for securing the hinge connection and spring device to the arms.

3. In a lifting device of the character described, a pair of elongated arms, a hinge connection between a pair of adjacent ends of the arms, a spring device associated with the hinged ends for tensioning the free ends of the arms in directions of separating movements, means associated with the arms intermediate the ends thereof for limiting separating movements of the free ends of the arms, said hinge connection including a hinge barrel with lateral butts, the butts being respectively secured to the inner sides of the arms and the spring device including a leaf spring, the hinged ends of the arms having end opening slots and the ends of the leaf spring being disposed in said slots and retained therein by the hinge butt securing means.

ANTONI OZDOBINSKI.
